United States Patent Office

Des. 178,592
Patented Aug. 28, 1956

178,592

TIRE

William F. Billingsley, Silver Lake, Ohio, assignor to The
B. F. Goodrich Company, New York, N. Y., a corpora-
tion of New York

Application July 15, 1954, Serial No. 31,450

Term of patent 14 years

(Cl. D90—20)

The drawing is a perspective view of a tire, showing my new design.

The dotted line disclosure is understood as representing the repetition of the full line disclosure in the drawing figure.

I claim:

The ornamental design for a tire, as shown and described.
